(57) CLAIM

The ornamental design for a brassiere, as shown and described.

DESCRIPTION

FIG. 1 is a perspective front view of a first embodiment of a brassiere according to my new and ornamental design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective front view of a second embodiment of a brassiere according to my new and ornamental design;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines at the underarms and at the shoulder straps that separate the front of the brassiere from the back of the brassiere represent the bounds of the claimed design while all other broken lines beyond the bounds of the claimed design are directed to environmental subject matter; the broken lines form no part of the claimed design.
